UNITED STATES PATENT OFFICE

JESSE VAN DYKE, OF KANSAS CITY, MISSOURI

HAT SUPPORT

Application filed February 23, 1928. Serial No. 256,240.

My invention relates to hat supports, the principal object being to support a hat for protection of the crown and rim during handling, for example, when enclosed in a container for delivery.

5 A further object of the invention is to provide hat supporting means which may be shipped in closely packed and unassembled condition for assembly at place of use.

10 In accomplishing these and other objects of the invention I have provided improved details of structure, the preferred forms of which are illustrated in the accompanying drawings, wherein:

15 Fig. 1 is a perspective view of the base member of my hat support.

Fig. 2 is a view of a band member adapted for bending into form for engagement with the base member.

20 Fig. 3 is a perspective view of the assembled elements of the device.

Fig. 4 is a central vertical section of a device on which a hat is mounted and of a paper bag in which the supported hat is enclosed.

25 Fig. 5 is a vertical section of the device illustrating the base member as constituting the bottom of a hat box.

Referring in detail to the drawings:

30 1 designates a base member comprising preferably a square or rectangle of cellular material such as heavy strawboard slotted on parallel paired lines, such as 2 and 3, the paired slits producing straps 4 comprising the portions of the board between the slits which may be lifted to produce pockets 5.

35 A hat receiving member 6 comprising a strip preferably of flexible and resilient material such as cardboard, is scored adjacent its ends 7 by transverse scorings 8, and the ends are preferably tapered for convenient insertion

40 into the pockets 5 of the base member, the resilience of the straps causing the base member to engage the ends of the strip with relative security upon release of the straps.

45 The body portion 9 of the strip between the scorings 8 is materially longer than the distance between adjacent edges of the straps so that when the strip is inserted, it is bent in a curved line to provide a loop and the portions of the body adjacent the scorings pro-

vide shoulders for retaining the strip in engagement with the straps. I also provide latching members 10 comprising tongues produced in the base member adjacent the straps by slitting the base member perpendicularly 55 to the slits that produce the straps, the tongues being adapted for being lifted to receive the portions of the body member adjacent the scorings for bracing the strip in installed position and also for latching the 60 ends of the strip against accidental slipping from the pockets or slits.

While the strip may be bent when it is installed on a base I prefer to confer a tendency to bend upon the band upon manufacture 65 thereof so that a slight influence will cause the band to assume its desired shape, the conferred condition being represented by the transverse lines 11 in the drawings.

The two members of the device are shipped 70 unassembled in plane position and thus occupy a small amount of space. The members may be assembled at any time to provide a conveniently available stock of hat supports ready for use, or may be assembled when a 75 hat support is required.

In assembly a strip may be bent into curved position by such process as passing it over the edge of a board, the conferring of a semi-permanent curvature being assisted by the 80 preferred treatment given upon manufacture. The strip tends, however, to return to straight position. The ends of the strip are bent on the score lines, and inserted under the straps of the base so that the outer edges of the ends 85 protrude from the exterior slits and bear upon the upper surface of the base, the curved loop tending to urge and latch the ends in the pockets.

The tongues are lifted and engaged with 90 the inside of the body portion of the loop and being relatively resilient, spring back to latch the loop in engagement with the straps. A hat may then be mounted on the base, the loop extending into the crown and tending 95 to support the same while the base member supports and protects the rim of the hat. The loop, as illustrated in the drawings, bears against opposite sides of the hat and, therefore, anchors it to the board or base 100

member so that it is retained in relatively fixed position on the base member whereby the edges of the base member protect the edges of the hat brim from distortion or injury and the hat is prevented from shifting from one side of the base member to the other.

5 A hat, designated 12 in the drawings, mounted on a base may be enclosed in a paper bag designated 13 for delivery.

10 Fig. 4 illustrates a modified application of the device wherein the base member comprises the bottom of a hat box 14, the retention of the hat by the arcuate strip anchored to the bottom of the box preventing the slipping of the hat towards the walls 15 as well as preventing the falling of the hat to the top 16 of the box in case the box should be overturned.

15 What I claim and desire to secure by Letters Patent is:

20 1. In a hat support, a base member having parallel pairs of slits, and a hat-receiving member having ends receivable respectively in said pairs of slits for attaching the hat-receiving member to the base member, one of said members having an outstruck tongue engageable with the other member for latching the members together.

25 2. In a hat support, a base member having parallel pairs of slits producing anchoring straps, a hat-receiving member having ends receivable under said straps for attaching the hat-receiving member to the base member, and resilient tongues on the base member perpendicular to the straps engageable with the hat-receiving member to latch the same.

30 3. In a hat support, a base member provided with paired straps and outstruck tongues adjacent said straps, and an arcuate 40 hat-receiving member having portions engaged by said straps for attaching the arcuate member to the base member and latched by said tongues.

35 4. In a hat support, a base member comprising a sheet having parallel straps, and a hat-receiving member comprising a strip of flexible material adapted for shaping upon insertion of the ends into engagement with said straps to limit the projection of the 50 ends through the straps, and an outstruck tongue on one member engageable with the other member for latching the strip to the sheet.

45 5. In a hat support, a base member comprising a sheet having parallel pairs of slits producing spaced straps, and a hat-receiving member having ends adapted for insertion into said slits for retention by the straps, and tongues outstruck from the base member 60 for latching the ends of the hat-receiving member in the slits.

55 6. In a hat support including a base member comprising a sheet having parallel pairs of slits producing spaced straps, a hat-receiving member comprising a strip of cellular 65

70 material provided with transverse scorings adjacent its ends, said strip being adapted for shaping upon insertion of the ends into engagement with said straps and bending of the strip at the scorings to limit the projection of the ends through the slits, and means on the sheet for latching the strip in shaped position.

75 7. In a hat supporting device, a base member comprising a piece of cardboard having parallel pairs of slits providing spaced straps and a hat receiving member comprising a band of cardboard having ends insertable into said pairs of slits for engagement by the straps and adapted for bending of the ends to provide shoulders to bear oppositely against the straps for retaining the hat-receiving member in engagement with the base member.

80 8. In a hat supporting device, a base member comprising a piece of cardboard having parallel pairs of slits providing spaced straps and a hat-receiving member comprising a band of cardboard having ends insertable into said pairs of slits for engagement by the straps and adapted for bending of the ends to provide shoulders to bear oppositely against the straps for retaining the hat-receiving member in engagement with the base member, and tongues produced in the base member by slitting the same perpendicularly to said first-named slits, adapted for latching the ends of the band in engagement with the straps.

85 9. In a hat box, a bottom member having transverse straps, an arcuate strip having outbent ends retained by said straps, and means including a tongue adapted to bear downwardly against the bottom member and outwardly against the strip for latching the strip in strap retained position.

90 In testimony whereof I affix my signature.
JESSE VAN DYKE.
